UNITED STATES PATENT OFFICE.

ARLIE C. BECK AND ALVIE S. MORNINGSTAR, OF BENTONVILLE, ARKANSAS.

GASOLINE CLARIFIER.

Application filed October 21, 1926. Serial No. 143,201.

This invention relates to gasoline clarifiers and more particularly to a device of this character adapted for use in cleansing the gasoline employed in cleaning establishments.

An important object of the invention is to provide a device of this character in which the cleaning of the gasoline is expedited and at the same time a product provided which 10 is free from impurities of any sort.

A further object of the invention is to provide a device of this character which prevents introduction of air into the cleaning tank with the gasoline. In many devices of 15 this character, the construction is such that air enters with the gasoline, with the result that the solution is disturbed and rapid clarification of the gasoline prevented.

A further object of the invention is to 20 provide a device of this character wherein the pressure applied to the gasoline injected into the casing is prevented from fluctuating rapidly, so that the contents of the container will move uniformly and the cleansing operation can accordingly be very accurately controlled.

These and other objects we attain by the construction shown in the accompanying drawings, wherein for the purpose of illustration is shown, a preferred embodiment of 25 our invention and wherein:—

Figure 1 is a vertical sectional view of a gasoline cleaner constructed in accordance with our invention;

Figure 2 is a section on the line 2—2 of 35 Figure 1;

Figure 3 is a section on the line 3—3 of Figure 1.

Referring now more particularly to the 40 drawings, the numeral 10 indicates a casing, at present shown as rectangular in form and has its bottom in the form of a funnel 11, the lower end of which is provided with a valve control drain opening 12. Immediately 45 above the upper end of the funnel, the casing 10 is provided with an outlet 13, while at its upper end a further outlet 14 is provided. The top of the casing is provided with a removable cap 15. Extending into 50 the casing adjacent the lower end thereof is a conduit 16, the inner end of which is provided with an extension 17 co-axial with the casing and having at its lower end a distributor head 18 from which radiate a plurality of discharge nozzles 19. The outer

end of the conduit 16 communicates with a vertical stack 19^a of greater diameter than the conduit. The upper extremity of this stack is vented at 20 and is provided with an inlet 21 arranged below the vent and adapted for connection with the usual gasoline pump of the cleaning apparatus. Adjacent the casing 10, the conduit 16 has associated therewith a funnel 22, the outlet 23 of which is valve-controlled. This funnel provides a means for introducing to the funnel-shaped bottom 11 of the casing 10 a commercial alkalinized solution, such as is ordinarily employed in cleansing gasoline.

Arranged within the casing 10 is a rack 70 comprising vertical supports 24, the lower ends of which rest upon the inner faces of the walls of the conical bottoms 11 adjacent the tops thereof. These racks support a plurality of horizontally extending baffle 75 plates 25, each of a length less than the width of the casing and each having one end extending close to the wall of the casing and the opposite end spaced therefrom.

The spaced ends of the baffle plates 25 are alternated, so that a circuitous path is provided for liquid arising through the plates. The edges of the baffle plates 25 which are spaced from the casing are each provided with downwardly bent lips 26 arranged at 80 an acute angle to the plate and adapted to catch any floating material carried by the liquid passing between the plates. Above the channel 27 provided between the uppermost plate 25 and the wall of the casing, a 85 further baffle plate 28 is disposed to insure proper distribution of liquids and prevent these liquids from arising in a vertically moving current which would cause all im-

purities carried thereby to engage against 90 filter 29 arranged above the rack. The filter 29 is formed by providing two screens 30 and 31 of suitable mesh and of a size to fit within the walls of the casing. The screen 30 rests directly upon the upper ends of the standards 24 of the rack and upon the screen is placed a suitable filtering medium, such as cotton seed hull, cotton batting, waste or similar material which will remove from the liquid any floating substances, such as might 95 pass the lips 26. The screen 31 is then placed on top of this material and has its upper surface immediately below the level of the outlet 14. The stack 19^a hereinbefore mentioned should have its upper end well 100

105

110

115

spaced above the upper end of the container 10.

In operation, gasoline is introduced through the pipe 21 to the stack 19^a and through this stack will apply static pressure to force the gasoline into the container 10. Within the stack, any air which may be contained in the gasoline separates and passes through the outlet 20. The gasoline 10 entering through the head 18 and nozzles 19 is thoroughly intermingled with the alkali solution and separating therefrom by gravity leaves within the alkali solution, the major portion of the dirt carried thereby. As 15 the gasoline rises through the path provided by the baffle plates 25, floating substances will be collected by the lips 26 and removed therefrom. In its passage through the filter 29, any other substances carried thereby will 20 be removed. Pure gasoline is withdrawn from the outlet 14 and returned to the cleaner. Dirty gasoline and muck may be removed through the outlet 13 and the alkali solution and any sediment contained 25 therein may be drawn through the outlet 12. It is pointed out that the filter 29 may have its filtering material readily replaced at any time and that in cleaning the filter, it is merely necessary to remove the cap 15, withdraw 30 the filter and rack for cleansing and then

withdraw the dirty gasoline and alkali solution.

Since the construction hereinbefore set forth is capable of a certain range of change and modification without materially departing from the spirit of the invention, we do not limit ourselves to such specific structure except as hereinafter claimed.

We claim:

A gasoline clarifier comprising a casing 40 having a funnel-shaped bottom wall, a filter disposed across the upper part of the casing, a conduit pipe passing through the side of the casing, and having an end extension disposed co-axial with relation to the funnel-shaped wall of the casing, a distributing head located in the funnel-shaped wall of the casing and attached to the extension of said conduit, radially disposed nozzles carried by the head, a vertically disposed stack 45 for supplying gasoline to the conduit, said stack having its upper portion disposed above the level of the filter, and means for supplying an alkali to the conduit between the stack and the casing.

In testimony whereof we hereunto affix our signatures.

ARLIE C. BECK.

ALVIE S. MORNINGSTAR.
